GAME

Arthur L. Rausher, Chicago, Ill.

Application July 14, 1938, Serial No. 219,235

2 Claims. (Cl. 273—96)

This invention relates to games and more particularly to indoor manually operated games of skill.

One of the objects of the invention is the provision of a new and improved game wherein is employed a board having pawns or objects thereon which are adapted to be projected into the air by striking the same with a bat, striking implement or playing stick and caught by the player 10 in a receptacle mounted on the bat or playing stick.

A further object of the invention is the provision of a new and improved game that is inexpensive to manufacture, highly entertaining, 15 easily learned and a game in which skill plays an extremely important part.

Other and further objects and advantages of the invention will appear from the following description taken in connection with the accompanying drawing in which—

Fig. 1 is a plan view of the board and objects thereon;

Fig. 2 is a perspective view of the playing rod or stick;

Fig. 3 is a plan view of one of the objects; and Fig. 4 is a side elevation.

Referring now to the drawing, the reference character 10 designates the board on which the game is played. This board may be of the usual 30 or any well known type, either foldable or otherwise as is common in such constructions. The board is provided with a ring or circle 11 within which a plurality of objects 12 are placed. These objects are adapted to be struck by a playing stick 35 13 to cause them to be projected into the air and to be caught in a receptacle mounted on the stick.

The objects 12 are of different classes and except for two of the classes, there are a plurality of objects in each class. For convenience of description, the different groups or sets of objects 40 12 will be designated by the reference characters 12a, 12b, 12c and 12d with the additional objects 12e and 12f.

The groups 12a, 12b, 12c and 12d will each contain a plurality of objects of the same color for each group but of different colors for the different groups, as for instance, the individual objects for the group 12a will be white in color, 12b will be green, 12c will be red and 12d will be brown. Any 50 desired number of groups may be provided, four being shown for illustrative purposes. If desired, in order to increase interest in the game, the objects may have their upper surface either painted or carved to simulate an animal, insect, or the like. In the form of the construction em-

ployed to illustrate the invention, the objects of the different groups have the image of a beetle or bug on each side. As shown, these beetles are formed by raised portions on the surface of the objects, Figs. 3 and 4. The object 12e has the 5 image of a spider on it which may be colored black and the object 12f has the image of a ladybug which may be spotted, as shown.

Each of the objects 12 may be considered as being formed of any suitable material and is preferably, though not necessarily, rectangular in plan. Each object has one end rabbeted or undercut to form an overhanging projection 14 and its other end reversely rabbeted or overcut to form a projection 15 which, when the object is turned 15 upside down, will form an overhanging portion similar to that shown at 14.

The playing stick or rod 13 is an elongated member which is adapted to be held in the hand of the operator, as shown in Fig. 2. The outer or 20 free end may be provided with a rubber tip 16 and the inner end of the playing stick is provided with a receptacle 17 rigidly mounted thereon which will be adjacent to the hand of the operator.

In the playing of the game, the operator, by means of the playing stick 13, taps or strikes the overhanging portion or projection 14 of a bug which causes the same to leap or to be projected 30 into the air and the operator attempts to catch or capture the same in the receptacle 17 which, if accomplished, counts a predetermined number of points for the player.

Any suitable rules may be employed for playing the game but the following have been found 35 to be very satisfactory. The objects are all placed within the circle on the board in no particular order but are separated sufficiently far apart that they may be tapped with the playing stick 13. The players take turns in tapping 40 or striking the bugs, the white bugs being removed first, then the green, the red and finally the brown. When a player taps one of the bugs and fails to catch it in the receptacle 17, he loses his turn. If he catches the bug in the receptacle, 45 it will count a predetermined number of points; for instance, the white bugs may each count 5, the green 10, the red 15 and the brown 20, as indicated at 30 on the drawing. Any bug accidentally moved without the ring or circle 11 must be 50 replaced within the ring. A player continues to play until he fails to catch the object in the receptacle 17. When, however, he catches two bugs in succession, then he must strike the spider and if he catches the spider in the receptacle, he 55

proceeds as before in striking a bug and catching the same. If however, he fails to catch the spider in the receptacle, he loses his turn and is penalized by being compelled to return the last 5 bug caught to the board. When all of the bugs of the different groups have been removed from the board, the next player taps the ladybug and if it is caught within the receptacle, he is credited with an additional fifty points. If, however, he misses, the next player takes his turn and so on 10 until the ladybug is caught within the receptacle. Any predetermined number of points, which, with the values given above, are multiples of a hundred, as agreed to by the players, may constitute 15 a game. The values given the different objects may be varied as agreed to by the players, the values given above being for illustrative purposes only.

It is thought from the foregoing, taken in connection with the accompanying drawing, that the construction and operation of my device will be apparent to those skilled in the art and that changes in size, shape, proportion and details of construction may be made without departing 20 from the spirit and scope of the appended claims. 25

I claim as my invention:

1. A playing stick for striking the overhanging portions of a gaming object for projecting the same into the air, said stick being straight and rectangular in cross-section throughout its length, a rubber tip on the striking end of said stick, and a receptacle opening upwardly on said stick adjacent to its opposite end and adjacent to the hand of the operator when the stick is in use, said receptacle being adapted to catch the projected object. 5

2. A playing stick for striking an object having parallel upper and lower surfaces provided with an undercut on one end of said object and an overcut on the other end thereof, said stick being rectangular in cross-section and of substantially uniform cross-sectional area throughout its length and having a rubber tip on its outer end and a receptacle on one of its sides adjacent to the inner end thereof and opening upwardly whereby said object, when struck with said stick by a player, will be projected upward and may be caught in said receptacle by said operator without rotating said stick. 10 15 20
